UNITED STATES PATENT OFFICE.

ARMIN SEIDENBERG, OF NEW YORK, N. Y.

PROCESS FOR FRACTIONATING COMPOUND SUBSTANCES CONTAINING INGREDIENTS OF CLOSELY-RELATED SOLUBILITY.

1,340,186.

Specification of Letters Patent. Patented May 18, 1920.

No Drawing.

Application filed August 10, 1918. Serial No. 249,260.

To all whom it may concern:

Be it known that I, ARMIN SEIDENBERG, a citizen of the United States, residing at the city, county, and State of New York, have 5 invented a certain new and useful Process for Fractionating Compound Substances Containing Ingredients of Closely-Related Solubility, of which the following is a specification.

10 My invention relates to a method of separating compound substances, such as fats, by taking advantage of the differences in solubility existing among their constituent parts.

15 When the ingredients to be separated are closely related in solubility, such as the various glycerids that constitute the vegetable or animal fats, or the individual members of the paraffin series that constitute many 20 mineral oils, considerable difficulty has heretofore been experienced in making separations even into groups, without including appreciable quantities of other groups.

The principal object of my invention is 25 to provide a process whereby the constituent parts may be more easily and completely separated than by any method, entailing the use of solvents, heretofore known or used.

According to my invention, I separate the 30 parts or ingredients by first dissolving the substance in a solvent composition containing components of different degrees of solvent action, and then gradually and uniformly removing said components from the 35 solution in the general order of their solvent action on the ingredients to be separated.

The conditions which are required for securing the best results are the most minute 40 gradation attainable in the differentiation to be effected between the different ingredients or parts to be separated, and as wide and instantaneous a uniformity of action throughout the entire solution as is possible, 45 so that the proximate points that indicate the greatest condition of insolubility for each ingredient or constituent part of the compound substance may be approached, one after the other, with as little overlap- 50 ping as possible, and at the same time uniformly throughout the solution. It is the aim of the method herein described to accomplish this to as great an extent as possible.

In carrying out my invention I dissolve 55 the compound substance to be fractionated in a solvent composition containing two or more components of different degrees of solvent action and volatility.

The components are usually, though not 60 necessarily always, miscible in each other. If desired the composition may contain, in addition to the solvent components, a component having no, or only very slight, solvent action upon the dissolved substance 65 such as water.

The character of the solvent components is such that the one or more which exert the greatest solvent action upon the least soluble ingredient or part to be separated are 70 the most volatile, while the one or more which exert the least solvent action are at the same time the least volatile.

After the solution has been formed the solvent components are removed with an 75 accompaniment of thorough agitation by volatilization or otherwise in the general order of their solvent action on the ingredients or parts to be separated. In this way 80 the ingredients or parts will be separated in the inverse order of their solubility, that is to say, the least soluble ingredient or part will be precipitated or thrown out of solution first and so on.

The solvent components are preferably 85 removed from the solution by passing, either by increased or reduced pressure (or suction), a current of air or other gas through the solution at an appropriate rate of speed. Other suitable means such as, for example, 90 reduction of pressure alone or mechanical agitation of the solution or combinations of these or other means may be employed for removing the solvent components.

Since, as is well known, the vaporization 95 of a liquid produces a reduction in its temperature, it is possible by using a low boiling point liquid to secure a very low temperature. By regulating the speed of removal, this may be attained as gradually 100 as may be desired. The extent of the temperature decrease may, if desired, be regulated, although not finely graded, by means of an outside temperature control.

It is also well known that the extent of 105 the solubility of the great majority of substances in various solvents, decreases with a decrease in the temperature of these sol-

vents, and in all cases also with the quantity of the solvents. The passage through the solution of a current of air or other gas is accompanied by a complete and uniform 5 agitation of the entire solution and therefore produces a gradual and uniform reduction of the temperature and a gradual and uniform volatilization of the solvent components. By this means, at any instant of 10 time, a very minute amount of solvent is removed simultaneously and uniformly from every part of the solution and a very minute decrease of temperature takes place simultaneously and uniformly in every part 15 of the solution. Due to this the ingredients of the dissolved substance will be separated with the greatest possible degree of refinement and with the least possible overlapping, since the condition of increasing in- 20 solubility (of the various ingredients) is progressively produced and as gradually and uniformly as is possible under the conditions.

During the process of removing the more 25 volatile component or components, the less volatile component or components are usually also removed to a slight extent. When all or almost all of the first mentioned component or components has been removed the 30 remainder of the solvent can also be removed by continuing the process until the entire amount of substance held in the solution has again been thrown or separated out.

The method may also be applied to a 35 series of non-miscible solvents that on being allowed to rest will form into separate zones. Combinations of this type may be secured either at the start or as a result of the removal in part or entirely of one or more 40 of the components used as solvents. In this case the various ingredients to be separated are divided among the various zones according to their relative solubility in those zones, and the proportion and amount of dissolved 45 substance in any zone may be regulated, as already described, by removing therefrom the more volatile component.

As a specific example of a solvent composition that may be used to fractionate the 50 ingredients or parts of a fat, such as tallow, may be cited a composition of ethyl alcohol and ethyl ether. The molten tallow is dissolved in a mixture ten times its volume, consisting of ethyl ether and ethyl alcohol 55 (absolute) in equal proportions. If necessary the solvent is warmed slightly to secure complete solution and then allowed to cool again. Any solid matter that settles out on cooling is filtered off by any of the 60 usual methods as residue A. The filtration should be thorough and as much of the solvent as possible removed from the residue.

Through the liquid solution air is then 65 aspirated until the liquid is reduced to about

one-half its original volume. The precipitate which has begun to show when about three-quarters of the liquid has been removed is separated from the liquid portions by filtration as residue B. Through the 70 clear filtrate air is again aspirated until it is again reduced to one-half its volume. On allowing to stand the liquid which is now turbid separates into two distinct liquid layers each of which is entirely clear. These 75 are now siphoned off from each other. The upper liquid layer leaves practically no residue on evaporating off the volatile portion. The lower layer on removing the volatile solvent by evaporation contains practically 80 all the remaining fatty material (residue C). By combining residue A and residue B, practically all solid fat in the tallow can be obtained, while practically all of the liquid fat will be contained in residue C. 85 This latter is the portion in tallow of most value in the manufacture of oleomargarin. By refluxing each of these fractions in the manner described, they can be further purified.

While in the foregoing description the solvent composition has been considered as composed entirely of liquids, it may also contain substances which at ordinary atmospheric temperatures are gases or solids.

The ingredient or constituent to be separated from the solution may be thrown out or precipitated in the solid or liquid state, or it may be separated by forming as a result of the process, a liquid zone distinct 100 from the rest of the solution with part or parts of the components forming the solvent composition, or otherwise it may be secured by being dissolved or abstracted by a zone already formed at the start by a change 105 effected during the process in the zone in which it was originally dissolved.

What I claim is:

1. A process of fractionating a compound substance containing ingredients of closely 110 related solubility which consists in first dissolving the substance in a plurality of solvents of different degrees of solvent action and volatility, said solvents being of such character that those having the greatest 115 solvent action on the least soluble ingredient or ingredients are the most volatile and those having the least solvent action on said ingredient or ingredients are the least volatile, and then gradually volatilizing the solvents 120 so as to precipitate or separate the ingredients in the inverse order of their solubility.

2. A process of fractionating a compound substance containing ingredients of closely 125 related solubility which consists in first forming a solution by dissolving the substance in a composition containing components of different degrees of solvent action and volatility, said components being of such character that those having the greatest 130

solvent action on the least soluble ingredient or ingredients are the most volatile and those having the least solvent action on said ingredient or ingredients are the least volatile, and then passing a current of gas through the solution so as to agitate it and to gradually and uniformly reduce the temperature of the solution and to gradually and uniformly volatilize the components of the solvent composition, whereby to gradually and uniformly precipitate or separate the ingredients in the inverse order of their solubility.

3. A process of fractionating a compound substance containing ingredients of closely related solubility which consists in first dissolving the substance in a plurality of sol-

vents of different degrees of solvent action and volatility, said solvents being of such character that those having the greatest solvent action on the least soluble ingredient or ingredients are the most volatile and those having the least solvent action on said ingredient or ingredients are the least volatile, and then allowing the solvents to evaporate accompanied by agitation, so as to gradually and uniformly reduce the temperature of the solution whereby to gradually and uniformly precipitate the ingredients in the inverse order of their solubility. 30
